UNITED STATES PATENT OFFICE.

EARLE C. POWERS, OF STRATFORD, NEW JERSEY, ASSIGNOR TO B. F. STURTEVANT COMPANY, OF BOSTON, MASSACHUSETTS, A CORPORATION OF MASSACHUSETTS.

METHOD OF DRYING HOSIERY.

Application filed April 12, 1922. Serial No. 552,013.

To all whom it may concern:

Be it known that I, EARLE C. POWERS, a citizen of the United States, residing at Stratford, in the county of Camden and State of New Jersey, have invented certain new and useful Improvements in Methods of Drying Hosiery; and I do hereby declare the following to be a full, clear, and exact description of the invention, such as will enable others skilled in the art to which it appertains to make and use the same.

This invention relates to a method of drying hosiery and more particularly to a method of drying silk hosiery.

During the manufacture of hosiery, the excess or surplus moisture is removed from the wet stockings as they come from the dyeing or bleaching operations by a centrifugal extractor so that the stockings as they arrive at the dry room are in a condition which may be regarded as damp. At the present time it is the practice to remove the remaining moisture in the stockings by subjecting them to the action of highly heated air with- 25 in drying apparatus of either of two general types.

The type of drying apparatus most commonly employed at the present time comprises the so-called cabinet drier which consists of a relatively large chamber within which air heated well above the boiling point of water is circulated at a slow rate, being passed vertically through a series of superposed racks or trays of stockings. The damp stockings which have been first boarded, i. e. drawn over suitable forms, usually of thin wood, are supported on their edges side-by-side on trays within the drying chamber. With the ordinary grades of stockings, the drying of each tray of stockings which usually consists of one dozen stockings, is completed in a period of approximately six to eight minutes, and the temperature employed within the drying apparatus is purposely maintained sufficiently high so that the drying operation may be completed within this period of time.

The other type of drying apparatus comprises the so-called automatic drier in which the stockings are drawn by the operator over a series of continuously moving forms. The forms and stockings are caused to traverse a high temperature drying chamber, the length of time that the stocking is within the chamber and the temperature of the air itself be-

ing controlled to dry the stocking by the time it has completed its journey through the apparatus.

In both types of driers, the drying effect is secured almost entirely by the high temperature employed, the air being heated well above the boiling point of water, usually to approximately 220 to 300 degrees F., and the circulation of the air being at relatively low velocity.

The individual fibres of the stockings, and particularly of silk stockings, contain volatile constituents and natural oils which impart to the fibres and to the stockings themselves desirable qualities of flexibility, softness and durability. With the methods at the present time employed for removing the moisture from the stockings, these volatile constituents, oils and even the fibres themselves, are changed from their natural state due to the baking effect resulting from the extremely high temperatures employed in drying the stockings in commercial quantity and at the rate necessary for commercial production. As a result, the wearing qualities of the finished stockings are impaired and the loss of the oils and other volatile constituents imparts harshness and brittleness to the fibres. In addition, the various organic dyes which are employed for imparting desired shades and colors to the stockings are themselves altered or changed in constitution during the high temperature drying operation, so that inferior lustre and finish are imparted to the dried stockings.

The object of the present invention is to provide a method of drying hosiery in a novel and superior manner by which superior wearing qualities, finish and lustre may be imparted to the dried stockings.

With this object in view, one feature of the present process contemplates the utilization of a rapidly moving current of low temperature air to accomplish the drying operation in contradistinction to the high temperature, slow moving air currents heretofore employed. In this manner the disastrous effects of the high temperatures heretofore employed are successfully avoided without in any way interfering with the economical drying of the stockings on a commercial scale.

Further features of the process reside in the methods of handling the stockings during the drying operation and of the man-

ner in which the air currents are caused to traverse the stockings during the drying operation, in order that the maximum drying effect may be obtained with a minimum consumption of power. These and other features of the invention will be hereinafter pointed out and particularly defined in the claims.

- In the drawings illustrating the apparatus in which the present methods of drying hosiery are preferably carried out, Figure 1 is a vertical longitudinal section of the apparatus and Fig. 2 is a plan of the same partly in section.
- 15 In the illustrated apparatus in which the present drying process is preferably carried out, the damp stockings in the condition in which they come to the dry room are boarded upon wooden forms in the usual manner, 20 the upper surface of the drying apparatus being arranged at such height from the floor as to afford a convenient work table on which the stockings may be boarded by an operator and then transferred to the drying compartments. The drying apparatus comprises briefly a closed chamber or cabinet, the upper portion of the interior of which contains several drying compartments to hold the stockings. Beneath these compartments in the lower portion of the apparatus is a heating chamber having a heating coil the steam supply to which is automatically controlled by a thermostatically operated valve. The circulation of air is 30 effected by means of motor driven fans, one for each compartment, at one end thereof. The circulation of air through the drying compartments is controlled by dampers operatively connected to the compartment doors so that when a door is opened to remove and replace stockings, the circulation of air through that particular compartment will be stopped, being renewed as soon as the door is closed. An open exhaust flue extends 40 across the apparatus between the drying and heating compartments through which air is withdrawn from the apparatus when the door is opened, fresh air entering through the door to replace that withdrawn.
- 45 Referring to the drawings, the cabinet or chamber 10 is formed by a steel frame 12 to which insulating sides 14 and top 16 are secured. The upper half portion of the chamber 10 is sub-divided into a plurality of drying compartments 20 herein shown as three in number and within which the drying operation upon the stockings is performed. The top and sides of each compartment are formed by inverted U-shaped sheet metal members 21 which rest side-by-side upon transversely extended supporting bars 22 forming part of the frame 12 of the drier. The bottoms of the compartments 20 are formed by the top surface of an exhaust duct 24 arranged to extend transversely of
- the chamber 10, as shown in Fig. 1, and terminating in the upwardly extending exhaust flue 26 which is connected with suitable piping and an exhaust fan (not shown). The length of the exhaust duct 24 is such as to leave open spaces 32 in the bottom of the drying compartments through which air may circulate from each drying compartment down into the space below the drying compartments comprising a heating chamber 34. Within the heating chamber is a series of steam pipes 35 connected to headers 36 and the steam supply through the pipe 37 is controlled by a thermostatically operated valve 38 controlled by thermostat 39. By these means the temperature of the circulating air may be automatically and accurately controlled so that a relatively low temperature as compared with prior apparatus and methods may be insured and a superior quality of product obtained.
- 55 While the temperature may be varied to some extent in my improved process, owing to variations in the character of stockings to be dried and in the velocity of the circulating air, in no event must such temperature exceed 212 degrees F. Preferably a temperature of from 120 degrees to 200 degrees F. will be employed. I have found in practice that with a certain quality of silk stockings now being put upon the market, a temperature of 125 degrees F. with an air velocity of one thousand feet per minute give excellent results.
- 60 The drying of the stockings within the drying compartments is accomplished by the rapid circulation of air produced by fans 42, one for each compartment. The fans 42 are positioned at the rear of the compartments 20 being mounted upon the ends of driving shafts 44 journaled in bearings 46 upon the ends of angle supporting bars 48, and extended through the rear wall of the chamber 10 as shown. An individual motor 50 for each fan is mounted outside the drier upon the extended end of the angle supports 48 and serve through the shafts to rotate the fans at high speed, so that a relatively high air velocity is obtained, preferably from 750 to 2000 feet per minute.
- 65 During the normal drying operation, the boarded stockings having been placed within the drying compartments and being supported therein upon suitable trays, as will be described, the compartment doors 60 are closed and dampers 62 operatively connected therewith, as will be described, are swung from the full line to the dotted line position, Fig. 1, thus establishing circulation of air in a closed cycle from the fans through the drying compartments, thence through the openings 32 downwardly into the heating chamber 34 common to all three drying compartments, where the air is again raised in temperature and then drawn up.

wardly over the dampers 62 into the supply chambers 65 for the fans and again caused to traverse the foregoing cycle. When the doors 60 are opened, the dampers 62 are closed, thus cutting off the circulation of air by the fans and permitting moist air from the drying compartments to be drawn up the exhaust duct and fresh air to be drawn into the compartments through the open door. Partitions 63 are provided in the forward part of the heating chamber 34 to prevent the fresh air incoming through one door from mixing directly with the circulating air in the next compartment.

In order to direct the air from the fans onto the heel and toe portions of the stockings so that the maximum drying effect may be obtained at these points which are in practice the most difficult to dry, each fan and drying compartment is provided with a deflector 70 arranged to cooperate with the periphery of the fan and to converge the air current from the fan and to direct it directly upon the toe and heel portions of the stockings. The deflectors 70 are preferably formed of sheet metal in the shape of a frustum of a pyramid the smaller ends thereof being secured to the rear end of the walls of the drying compartment. The rear or enlarged ends of the deflectors are bent over a plate 73 extended across the entire width of the drier, being riveted or otherwise secured to the side walls of the chamber 10 and having circular openings therein with which the periphery of the fans cooperate.

The trays upon which the stockings are supported each comprise rectangular framework 74 arranged to slide in longitudinal supporting bars 75 and having a series of guides 76 upstanding therefrom at their forward ends and a combined heel and toe rest 78 at the rearward end. The combined heel and toe rest may be adjusted with respect to the frame, being retained in adjusted position by a series of notches 80 in the frame, one or another of which is engaged by a lug depending from the rest. Each tray is adapted to support a dozen boarded stockings within each compartment.

In assembling the boarded stockings in the trays within each compartment, a door 60 of one compartment is opened into a horizontal position and the tray drawn part way out, being supported in its extended position upon the horizontal door 60 which, in turn, is supported in open position by connections with the dampers 62, the latter also serving to cause operation of the damper in synchronism with the door. For this purpose each damper 62 is connected through a link 84 to one arm 85 of a bell crank 86 pivoted at 88 to one of the longitudinal supporting bars 75 for the trays. The second arm of the bell crank 86 is connected by a longer link 89 to the door 60 of the drying compartment. With this arrangement, when the door is open, the damper 62 is swung into a closed position illustrated in full lines, Fig. 1, and when the door is closed, again permitted to drop into its open position illustrated in dotted lines, Fig. 1. With this arrangement, whenever the door is opened, the damper immediately cuts off the supply of air to the suction side of the fan from the common heating chamber 34, so that circulation of the air by the fan in that particular compartment is cut off. At the same time the suction in the exhaust duct operates to draw into the heating chamber through the open door a fresh supply of air from the dry room, so that not only is an out blast of moist air from the drying compartment through the open door avoided, but at the same time sufficient fresh air is automatically introduced into the drier to maintain the air within the same in a condition most favorable to drying a fresh supply of stockings.

The operation of the illustrated drier according to my improved method is as follows: The operator boards the stockings one dozen at a time, using the top of the drier as a boarding table. As each dozen is boarded the operator opens the door to one of the drying compartments, thereby closing the damper to cut off the supply of air to the fan of that particular compartment and permitting the withdrawal of air from the drier through the exhaust flue and the admission of a fresh supply of air through the open door. He draws out the tray, replaces the dried stockings by the dozen just boarded and then closes the door, re-establishing the circulation through the compartment. The operator then removes the dried stockings from the boards and places undried stockings thereon, and substitutes them for the dried stockings of another compartment, and continues in this manner using the three compartments in rotation. Each dozen stockings are then dried for the period of time required by the operator for boarding, placing, removing and stripping two dozen stockings, which is ordinarily from ten to fifteen minutes and sufficient for the proper drying of the stockings.

Owing to the fact that the air is of relatively low temperature, all liability of damage to the stockings is avoided and a very superior product is obtained. The relatively high velocity of the circulating air breaks up the surface film of moisture in the hosiery and enables the air to penetrate the interstices of the knitted material so that the moisture is removed from both the surface and interior of the fabric. This results in a rapid drying of the hosiery. At the present time, after the stockings are dried they are usually subjected to paper pressing to

remove wrinkles and improve the finish. By the present method of drying in which the stockings are subjected to the action of the air flowing in a direction from the foot to the top of the stocking, the wrinkles are eliminated and such a finish imparted to the stocking that pressing can be dispensed with.

No claims are made in this application to the apparatus illustrated in the accompanying drawings as such apparatus forms the subject matter of, and is claimed in my pending application filed April 12, 1922, Serial No. 552,014, for hosiery drier.

Having thus described the nature of my improved method and an apparatus for carrying it out, what is claimed is:

1. The method of drying hosiery and the like which consists in directing a stream of air at high velocity on to the foot portion 20 of stockings and then longitudinally of the stockings to the top thereof.

2. The method of drying hosiery and the like which consists in providing a circulating flow of drying air, dividing such flow 25 for a portion of its circulation into a plurality of separated streams, subjecting lots of hosiery, each to one of the streams, and replacing each lot successively while the other lots are being subjected to the other streams and without interference therewith.

3. The method of drying hosiery and the like which consists in providing a circulating flow of drying air, dividing such flow for a portion of its circulation into a plurality of separated streams, subjecting lots 35 of hosiery, each to one of the streams, cutting off the flow of each stream successively and replacing each lot successively while the other lots are being subjected to the other streams and without interference therewith.

4. The method of drying hosiery and the like which consists in providing a circulating flow of drying air, dividing such flow

for a portion of its circulation into a plurality of separated streams, subjecting lots 45 of hosiery each to one of the streams, cutting off the flow of each stream successively and replacing each lot successively while the other lots are being subjected to the other streams, and introducing fresh air 50 into the separated streams.

5. The method of drying hosiery and the like which consists in providing a circulating flow of drying air, dividing such flow for a portion of its circulation into a plurality of separated streams, subjecting lots 55 of hosiery one to each of the streams, cutting off the flow of each stream successively and replacing each lot successively while the other lots are being subjected to the other streams, and simultaneously withdrawing a portion of the air and introducing fresh air into each separated stream while the lot of hosiery for such separated stream is being replaced.

6. The method of drying hosiery and the like which consists in heating a stream of air, dividing the stream into a plurality of separate streams, applying each stream to a single lot of hosiery, and combining the 70 streams again preparatory to re-heating.

7. The method of drying hosiery and the like which consists in subjecting the boarded hosiery to a circulation of air at low temperature and high velocity, the air being directed onto the foot of the stocking and then longitudinally of the stocking to the top thereof and thereafter being reheated and again directed onto the stocking.

8. The method of drying hosiery and the like which consists in heating a stream of air, directing the heated air against hosiery in a closed chamber, introducing fresh air into the chamber and heating the fresh air before it is directed against the hosiery.

EARLE C. POWERS.
